UNITED STATES PATENT OFFICE.

JOHN M. BARNEY, OF NEW YORK, N. Y.

ASH AND REFUSE HOISTING DEVICE.

1,321,412.

Specification of Letters Patent. Patented Nov. 11, 1919.

Application filed March 4, 1918. Serial No. 220,357.

To all whom it may concern:

Be it known that I, JOHN M. BARNEY, a citizen of the United States, and a resident of New York, in the county of New York and State of New York, have invented certain new and useful Improvements in Ash and Refuse Hoisting Devices, of which the following is a specification.

My present invention relates to an ash and refuse hoisting device, and particularly to a structure of this character which can be installed in a basement or ash pit of an apartment, office building, or the like, and which can be used in elevating cans or containers to a road or street level and then to raise the same to a height that the contents can be dumped into a wagon in which the ashes or refuse are to be carted away.

An object of my invention is to provide a device which can be installed in any basement or ash pit and which can be connected to be operated by a fluid pressure, which pressure can be obtained through connection to a water pipe, a steam boiler as for instance a heating boiler, or to other sources of supply of fluid under pressure.

A further object resides in providing means by which the main supporting or crane structure is retained in an elevated position and in such a relation that can or receptacle lifting means associated therewith can be used to hoist a number of receptacles from the basement or pit where the device is installed.

Another object lies in arranging fluid control means whereby both the movement and operation of the main supporting structure and of the receptacle hoisting mechanism can be controlled from the pit or from the street level, and in providing in conjunction with the main structure means by which the same is given a partial turn to swing the crane arm from which the receptacle is hoisted and to thus carry the can or receptacle out and over a wagon to which the contents is to be loaded.

A still further object is to provide in conjunction with the moving parts, means by which the pit or basement doors are moved to an open position, while at the same time retaining and guard means carried by the doors is brought into position to retain the doors in an open relation and to dispose a fence around the pit opening.

Yet another object is to arrange with the doors, an audible alarm means to be rendered

active by opening and closing of the doors and to thus give warning to pedestrians or other passersby.

Further objects of my invention will appear in the following detailed description, taken in connection with the accompanying drawing, forming a part of this specification, and in which drawings:

Figure 1 is a view taken in vertical section into a pit or basement and illustrating the preferred embodiment of my invention installed therein and with the parts in the raised or operative position.

Fig. 2 is a view similar to Fig. 1 and showing a slightly modified arrangement and construction of the parts.

Fig. 3 is a view made up somewhat after the manner of Figs. 1 and 2 and illustrating yet another modified form of the device.

Fig. 4 is a fragmentary elevational view of the structure shown in Fig. 3 taken substantially at right angles to the disclosure of this figure and with parts omitted and sectioned to better illustrate the structure.

Fig. 5 is a view in elevation of still another modified form of structure and showing the parts in the relation which they would assume when lowered to be received entirely within the pit or basement.

Fig. 6 is an elevational view taken substantially at right angles to the disclosure in Fig. 5 and illustrating the parts thereof.

Fig. 7 is a horizontal sectional view taken on the line 7—7 of Fig. 5.

Fig. 8 is a fragmentary sectional view illustrating a spring latch structure which is adapted for use to retain the main hoisting structure in the elevated position.

Fig. 9 is a fragmentary sectional view illustrating a gravity latch device which might be substituted for the spring latch device shown in Fig. 8.

Fig. 10 is a detail sectional view showing a cam arrangement adapted to impart a quarter turn swinging movement to the main elevating structure when the same is brought to the upper extreme of elevation to thus swing the crane arm thereof away from the pit or basement opening.

Fig. 11 is a detail view of an electrical contact structure which can be installed in conjunction with the pit or basement doors to cause energization of an electrical circuit in which an audible alarm device is installed and to thus give warning of opening and closing of the doors.

Fig. 12 is a sectional view showing the pit or basement doors closed and illustrating the preferred embodiment of door opening means.

5 Fig. 13 is a view similar to Fig. 12 but illustrating the doors in the open relation.

Fig. 14 is a sectional view substantially after the manner of Fig. 13 and showing a modified construction of door opening 10 means.

In the drawings, where similar characters refer to similar parts throughout the views, A designates a sidewalk or roof covering for a basement or pit, one of the walls of which 15 is shown at B, and this walk or roof has an opening C therein through which access is had to the basement or pit. As in disclosure in Fig. 2, it is preferable that the opening C be disposed adjacent a curb 1 which 20 bounds a roadway or street D, and when this arrangement is observed a wagon or cart E can be drawn up closely adjacent the opening so that cans or receptacles of ashes or refuse as hoisted through the opening can 25 be readily loaded bodily thereinto or can have their contents dumped.

In each of the embodiments of the invention as disclosed in the drawings, the principle and method of operation is substantially the same, the principal purpose in disclosing the several forms being to illustrate structures which might be used by being installed in pits, basements, or the like, of different heights and where different conditions are encountered. In the preferred embodiment, as illustrated in Fig. 1, a supporting bracket F is shown as secured to fixed and rigid parts of the pit or basement construction, and a supporting sleeve G is 30 mounted in conjunction with the supporting bracket. A crane upright H is slidably mounted through the sleeve G, and at its upper end has a crane arm I which is fixed thereon and which extends laterally. In 35 this adaptation, the raising of the crane upright H is accomplished through the use of a cylinder J which is located substantially vertically in line with the line of movement of the member H and which is rigidly fixed 40 upon the floor of the pit or basement by the use of the base flange 2, a piston K being mounted within the cylinder J to have reciprocatory movement throughout the 45 length thereof. In the present adaptation, 50 the crane upright H is made tubular, and fits telescopically over a supporting upright 3 which extends from the upper end of the cylinder J, and it will of course be understood that the member H slides upon this 55 supporting upright 3 and through the supporting sleeve G.

60 A shaft L is revolvably mounted in suitable bearings provided on the supporting sleeve G to turn upon a horizontal axis, and 65 this shaft has large and small cable drums

M and N keyed or otherwise rigidly mounted thereon. A cable 4 which is connected with the outer end of a piston rod carried by the piston K, is given a double turn around the small cable drum N, and is then led through an opening in the bracket arm 5 which is fixedly connected with the lower end of the crane upright H, the cable 4 having free sliding movement through the opening of this bracket arm. A counter-weight 70 6 is connected on the free end of the cable 4 and the cable is in fact made of such length that when fluid is supplied to cylinder J to cause the piston K to move downwardly therein and drawing tension is thus exerted 75 upon the cable 4, this cable will be taken in to bring the counter-weight 6 to bear beneath the bracket arm 5 and then the bracket arm will be carried up to cause the crane upright H to be led upwardly through the 80 supporting sleeve G. It will of course be understood that as long as the fluid pressure within the cylinder J is retained and the piston K is maintained substantially in the position shown by the dotted lines of Fig. 1, 85 the crane upright H will be held in the raised position, but that the upright will be retained in this position without maintenance of the pressure within the cylinder, it is preferable that a spring latch means as 90 shown in Fig. 8 or a gravity latch means as 95 illustrated in Fig. 9 of the drawings be employed.

With the latch device as illustrated in Fig. 8, the crane upright H is slotted 100 through as shown at 7, and a spring member 8 is secured in place to have the free end thereof project within this slotted opening 7, a lug 9 being carried by the free end of the spring member to extend beyond the 105 outer wall of the upright H. When the crane upright H has been carried in its upward movement to such a position that the lug 9 clears the supporting sleeve G, the spring 8 will cause this lug to be extended 110 substantially after the manner shown in Fig. 8 and in this relation of the parts, the lug will catch upon the upper end of the supporting sleeve or upon the supporting bracket F and in consequence the crane upright H will be retained in the elevated position until the lug 9 is moved back against the bearing pressure of the spring 8. With the gravity latch device as shown in Fig. 9, the links 10 and 11 are given swinging 115 120 mounting on the supporting sleeve G, upon an extension of the supporting bracket F, or at some other suitable point so that the free ends thereof will swing below the position assumed by the bracket member 5 when 125 the crane upright H has been raised to the position shown in Fig. 1, and at their lower ends these links 10 and 11 have the rollers 12 and 13 mounted to be disposed on their inner sides. A handle 14 is connected with 130

the free ends of the links 10 and 11 and is offset angularly to one side, substantially as shown in Fig. 3, the rest of the parts being such that as the crane upright H occupies the 5 lowest position, the rollers 12 and 13 will bear thereagainst and in consequence the links 10 and 11 will be held swung to one side, but as the crane upright is raised to the position shown in Fig. 1, the weight of 10 the handle 14 will be sufficient that the links 10 and 11 will be swung around their mounting and the rollers 12 and 13 will be carried to catch beneath the bracket member 5. When the rollers 12 and 13 are caught beneath the member 5, the crane upright will 15 be maintained in the raised position until the links 10 and 11 are swung to move the rollers from the position of engagement.

As the piston K is to be moved within 20 the cylinder J through the supply of fluid under pressure thereto and as the movement and operation of the parts is to be controlled either from within the pit or basement or from the sidewalk level, it is essential that a suitable piping system be arranged from a source of supply of fluid under pressure to the cylinder J, and that valves be entered into this piping system to allow for opening and closing of the 25 same by a party outside or within the pit or basement. A main fluid supply pipe 15 which has a cutoff valve 16 therein is connected with the upper end of the cylinder J through a pipe 17, and this pipe 17 has a valve 18 therein which might well be of the 30 three way type. A valve 19, which is also preferably of the three way type, is carried by the crane arm I, and a flexible tube 20 is led from the fluid supply pipe 15 to this 35 valve 19, a second tube 21 being led from the valve to connect with a pipe 22 which is joined in the pipe 17 between the cylinder J and the valve 18. Assuming that the cutoff valve 16 in the fluid supply pipe 15 is 40 open, the fluid under pressure will be supplied into the pipe 17 and the tube 20 up to the three way valves 18 and 19 respectively, and if one of these valves be set to establish connection to that length of the pipe 45 17 which connects with the upper end of the cylinder J, fluid will be supplied to the cylinder to cause the piston K to travel downwardly therein, and then when it is desired to release the pressure within the 50 cylinder so that the piston K will return to the upper end of the cylinder through the pulling strain exerted upon the cable 4 by the counterweight 6, either valve 18 or valve 19 will be opened to establish communication from the cylinder J to the atmosphere 55 or to a suitable exhaust pipe and thus the pressure is relieved within the cylinder and free return movement of the piston as allowed.

60 65 To guard against too quick movement of

the piston K in its downstroke when fluid is supplied to the upper end of the cylinder J, it is preferable that a liquid damper device be installed, and as is shown in Fig. 1, a pipe 23 is connected with the lower end 70 of the cylinder J and is then extended to a tank 24 which is supported at a height corresponding substantially to the highest point of movement of the piston K. A valve 25 is connected in the pipe 23, and assuming that the tank 24 is filled with water, oil, or other suitable liquid, the rate of flow of which through the pipe 23 can be controlled by manipulation of the valve 25, it will be seen that the speed with which the piston K is moved in its downstroke can be 75 very accurately controlled and regulated. 80

The crane arm I has cable wheels 26 and 27 mounted revolubly therein, and a cable 28 is carried over these cable wheels, that 85 end hanging over the wheel 27 is provided with a hook 29, and the remaining end being extended down substantially parallel with the crane upright H and carried around the cable drum M, to which this 90 end of the cable is anchored.

The structure as described will be installed for use substantially as is illustrated in Fig. 1, and assuming that the valves 18 and 19 are closed and have the vents thereof open 95 to exhaust the fluid contents in the upper part of the cylinder J, it will be of course appreciated that the crane upright H will be in a lowered position in which the crane arm I is below the top level of the walk or 100 cover A of the pit or basement, and both cables 4 and 28 will have the free ends thereof lowered and depending. The ash can or other receptacle to be hoisted is caught upon the hook 29, and then by opening either valve 18 or 19 to establish a fluid 105 supply connection from the pipe 15 and closing the remaining valve, fluid will be supplied to the upper end of the cylinder J and in consequence the liquid below the 110 piston K will be pushed back through the pipe 23 into the tank 24 and this piston will be lowered. Lowering movement of the piston causes the cable 4 to be drawn around the cable drum N about which it 115 is given a double turn, and in consequence this drum and shaft L will be revolved. The revoluble movement of the shaft L is transmitted to the cable drum M, and consequently the cable 28 is also taken in to 120 hoist the can or receptacle caught by the hook 29. When the cable 4 has been taken in sufficiently that the counter-weight 6 comes to bearing engagement against the lower side of the bracket arm 5, the hook 125 29 will have been raised to substantially a position illustrated, and through the fact that a direct pull is established against the bracket member 5, the crane upright H will be given upward sliding movement through 130

the sleeve G and will in consequence be raised to the position illustrated in Fig. 1 where the latch member will be free to move to a position to become operative in retaining the crane upright in this raised position. Now if the open valve be closed and be brought to a position to reestablish an exhaust connection from the cylinder through the vent to the atmosphere, the crane upright H will be still retained in the elevated or extended position, but through the force exerted by the counter-weight 6, the piston K will be raised within the cylinder J and the cable 4 will be drawn around the cable drum N. This movement of the cable drum N will cause the drum M to be revolved and in consequence the cable 28 is unwound therefrom and is free to run over the wheels 26 and 27 so that the hook 29 is lowered to a position to have other cans or receptacles attached thereto. Now upon again opening one of the valves to supply fluid under pressure to the cylinder J, the piston K will be again carried toward the bottom of the cylinder J and through the taking up of the cable 4, the cable drum will be again revolved and the cable 28 will be wound in to raise the can or receptacle attached thereto.

In the embodiment of the invention as shown in Fig. 2 of the drawings, the construction and arrangement of the parts is only slightly different and the operation is accomplished in substantially the same way as with the parts illustrated in Fig. 1. In this adaptation, the supporting upright 3' is shown as extending entirely down through the base portion 2', and the cylinder J', is mounted substantially parallel with and at one side of said supporting upright 3' the mounting of the cylinder being such that it is disposed at the top of the pit or basement. A cross-head 30 is connected with the supporting upright 3' adjacent the lower end thereof and a tubular upright 31 is supported on this cross-head 30 at its lower end and at its upper end has the cylinder J' alined therewith, then tubular member 31 thus acting to support the cylinder. A cable wheel 32 is mounted in suitable bearings provided on the cross-head 30 and the cable 4' is carried down through the supporting upright 3', around the cable wheel 32, and up through the tubular upright 31 to connect with the piston rod of the piston K'. It will of course be appreciated that the fluid supply pipe must be connected with the lower end of the cylinder J' so that the piston K' will be carried upwardly therein, and that the liquid damper pipe has connection with the upper end of the cylinder, but aside from this the remaining parts of the structure are substantially as shown in Fig. 1 and are arranged to operate in sub-

stantially the same way, in view of which fact similar reference characters have been applied thereto.

With the modification as illustrated in Figs. 3 and 4, the relative arrangement of the crane upright and the cylinder is substantially the same as shown in Fig. 2, but some departures are made in the manner of arranging the cable drums and of attaching and extending the cables. In this adaptation, the supporting sleeve G² is mounted in conjunction with the bracket F², and further support is given to the sleeve G² by a bracket 33 which is secured to the wall of the basement or pit, and is braced therefrom. The cylinder J² is also securely fastened to the wall of the basement or pit, and the tubular support is dispensed with, but aside from this, the crane upright H has sliding mounting through the sleeve G² in the same manner and the piston K² moves within the cylinder J² substantially as described in conjunction with the showing of Fig. 2. A base portion 34 is securely anchored to the floor of the basement or pit and has bearing standards 35 and 36 carried thereby, a drum shaft 37 being journaled in the bearing standards. A large drum 38, an intermediate drum 39, and a small drum 40, are all secured to be held upon the drum shaft 37 against turning movement, and it is preferable that the drum 40 be located vertically beneath the extending end of the piston rod by which the piston K² is carried while the drum 38 is located centrally beneath the supporting sleeve G². In this adaptation, the shaft L, together with the cable drums M and N, is dispensed with, and a cable wheel 41 is revolvably mounted on the bracket 33. The cable 28 is led over the cable wheels 27 and 26, and then down through the tubular crane upright H, and on down to the cable drum 38 with which the free end is fixedly connected, and a cable 42 which is connected with the piston rod moved by the piston K² is led over and anchored upon the cable drum 40 so that as the piston K² is moved within the cylinder J², the drum 40 will be turned and each of the remaining drums will be correspondingly revolved. A cable 43 is anchored on the intermediate drum and is carried over the cable wheel 41, the free end being connected with a counter-weight 6. When fluid under pressure is supplied to the cylinder J², the piston K² is given upward movement thereto and in consequence the cable 42 is unwound from the small cable drum 40, turning movement being thus imparted to the shaft 37 and consequently to the large and intermediate cable drums 38 and 39. The turning of these cable drums cause the cables 28 and 43 to be drawn in, and the crane upright H will be raised while at the same time a can or receptacle caught by the hook 29 will be correspondingly raised.

raised and will be hoisted through taking in of the cable 28. When the crane upright H has been raised to its uppermost position, the latch will automatically move to retain this position of the upright and then the fluid actuated parts can be employed to take in and let out the cable 28. In Figs. 5, 6 and 7, I have illustrated still another modified form of the structure, which modified construction partakes somewhat of the characteristics of the form illustrated in Fig. 2, this structure however, being adapted for use in a basement or pit having a relatively low roof or ceiling covering. A supporting sleeve G³ is carried from a supporting bracket F³, and the crane upright H³ is slidably mounted through the supporting sleeve, a tubular standard 44 being mounted by the base plate 45 to be supported from the floor of the basement or pit, and being received telescopically within the crane upright H³. This upright has the crane arm I³ at the upper end thereof and cable wheels are carried by the crane arm as is described in connection with the preferred embodiment. The sleeve G³ carries a member L³, which corresponds substantially to the shaft L, and which has cable drums M³ and N³ mounted thereon, these cable drums being cast in one piece or connected by a hub portion 46, so that turning movement of one drum will cause the remaining drum to be revolved. The cylinder J³ is mounted near the top of the basement or pit and substantially parallel with the crane upright H³, and the piston rod 47 extending from this cylinder has a cable wheel 48 carried at the outer end thereof. A supporting bracket member 49 is secured on the tubular upright 44 adjacent the base 45, and a cable wheel 50 is carried by this bracket member in line with the cable wheel 48, a cable wheel 51 being mounted in conjunction with the supporting sleeve G³ and being alined substantially vertically above the cable wheel 50, and it of course being understood that these several wheels are lined up with the cable drum N³. An anchor bolt 72 is connected in the floor of the pit or basement adjacent the base member 45, and a cable 53 is connected with the anchor bolt and is then led over the cable wheel 48, under cable wheel 50, up through the tubular standard 44, around cable wheel 51, about the cable drum N³, and then down alongside the crane upright H³ and through an opening in the bracket portion 5, below which the counterweight 6 is attached to the free end of the cable. By the arrangement in the manner as set forth, when fluid is supplied to the cylinder J³, through piping connections and valves which might be substantially identical with similar parts as shown in the remaining figures of the drawings, the piston rod 47 will be drawn in to the cylinder and in consequence the cable wheel 48 will be raised, thus accomplishing a double pull upon the cable 53 due to the fact that one end thereof is permanently attached to the anchor bolt 52. By this arrangement of the parts it is possible to use a cylinder in which the piston has a comparatively short stroke as the ratio movement imparted to the crane upright is as two to one with respect of the movement of the piston within the cylinder J³. A cable wheel 54 is mounted in conjunction with the bracket member 49 on an axis substantially at right angles to the line of the member L³, and a cable 55, which is anchored at one of its ends on the cable drum M³ is led down around this wheel 54, then up through the tubular standard 44 and through the crane upright H³, following which it is carried over the cable wheels of the crane arm I³. The free end of the cable 55 depends from the crane arm and has a hook 56 connected therewith to provide for attachment of cans or other receptacles in which the ashes or refuse is contained.

As the arrangement of the parts is such that a considerable length of cable must be carried over each of the cable drums N³ and M³, and as the most efficient action is accomplished when the cable exerts a straight and direct pull, it is preferable that provision be made for shifting of the cable drums as the cables are wound therearound. With this purpose in view, I provide external screw-threads on the member L³, and internally screw-thread the cable drums M³ and N³ together with the hub 46 by which the same are joined, the pitch of the thread being such that the endwise travel of the drums upon the shaft member L³ will be substantially relatively equalized with the length of the cable drums covered by each turn of the cable thereabout, and in this way the cables will at all times have tension exerted thereon in direct line to thus accomplish the most efficient hoisting action. It will of course be understood that when the crane upright has been raised to its uppermost position and has been caught to be retained by the latch portion, exhaustion of the fluid pressure within the cylinder J³ will leave the parts free so that the counterweight 6 will draw the cable 53 around the drum N³ and the several cable wheels to again extend the piston rod 47, and at the same time the cable 55 will be unreeled and the hook 56 will be lowered for the raising of the cans or receptacles subsequent to the one initially hoisted.

It will of course be understood that the crane upright will in each instance be free to have turning movement within the supporting sleeve, when the upright has been raised to the extended position, so that at least substantially a quarter turn can be given thereto to swing out or extend the

crane arm from which the cans or receptacles will be carried and to thus dispose the cans or receptacles over a cart or wagon drawn up alongside of the opening to the 5 basement or pit, and while this turning of the crane upright might be manually accomplished after the upright has been raised to its completely elevated position and is caught to be supported by the latch structure, and in fact the rollers 12 and 13 of the 10 structure as shown in Fig. 9 will act as thrust bearings in this turning movement, it is perhaps desirable that provision be made for accomplishment of this turning movement through mechanical means. While the 15 crane upright might be turned through the use of any well known or suitable means, the structure as disclosed in Fig. 10 is one which can be installed with the hoisting structure 20 as described and which will operate efficiently. As here shown, the supporting sleeve 56 has a slot or groove 57 provided on the inner wall thereof and this slot or groove is made cam-shaped so that from its lower to 25 its upper end it takes substantially a quarter-turn around the bore of the sleeve, and then at the upper end a straight branch 58 is provided. The crane upright has a pin or bearing roller 59 carried thereby to be received within the slot or groove 57, and as 30 this pin or roller 59 is disposed adjacent the lower end of the crane upright, it will not be carried into the groove 57 until the crane arm has cleared the sidewalk or cover of the 35 pit or basement, and then through following the groove 57, the pin or roller 59 will impart a quarter turn to the crane upright in consequence of which the crane arm will be swung out to dispose a can or receptacle 40 carried thereby substantially as is shown in Fig. 2, where it can be readily dumped or loaded into a cart or receptacle. Provision of the straight branch 58 as an extension of the groove 57 permits turning of the crane 45 upright manually when the same has been caught to be supported by the latch portion, but it will of course be understood that when the crane upright is to be lowered, it must be swung to such a position that the pin or 50 roller 59 will follow the curve of the groove 57, and with this purpose in view it is perhaps desirable that the lowest side of the straight extension 58 be sloped as indicated at 60, and with this arrangement it will of 55 course be understood that the pin or roller 59 will be guided into the groove 57 and as the crane upright is lowered will cause the same to be turned so that the crane arm will be brought to a relation to pass through the 60 opening in the sidewalk or cover A.

As is indicated in several main views and as particularly shown in Figs. 12, 13 and 14, the doors O and P are provided to close the pit or basement opening C, and in order that 65 pedestrians or other passersby may be

warned when the doors are to be opened, it is preferable that a bell or other audible signal and alarm means be provided to be rendered operative when the doors are being opened. In Fig. 11 of the drawings, I have illustrated contact means which might be embraced in an electric bell ringing circuit and installed in conjunction with the doors to cause the circuit and consequently the bell to be energized when the doors are being 75 opened. The door O has a link 61 connected therewith and this link is in turn connected at its free end with a block 62 mounted to travel in a trackway or guide 63, which part will be hereinafter more fully described. The block 62 has a spring contact finger 64 carried thereby and this contact finger or member is connected in one of the wires of the circuit embracing the alarm or signal device. A spring contact bar 65, 80 which has the ends thereof offset, is mounted upon the guideway portion 63 and insulated therefrom, the disposition of this contact bar being such that the spring contact finger 64 carried by the block 62 clears the same at the offset end but will engage with the main body portion as the block 62 is moved through opening of the door O. It will of course be appreciated that the contact bar 65 is connected with an opposite terminal in 85 the signal circuit, and when the parts are in the relation shown in Fig. 11, where the spring contact finger 64 is clear of the contact bar 65, the circuit connection will not be established, but as the contact finger 64 90 comes into bearing engagement with the bar 65, the circuit will be completed and in consequence the signal or alarm will be rendered operative.

With this third embodiment of the door 105 opening means as shown in Figs. 12 and 13, the track or guideway 63 is mounted substantially centrally between the hinged connections of the doors O and P, and is so disposed that the block 62 has sliding movement in a vertical path. The link 61 which is connected from the door O to the block 62, so mounting this block that as the door O is opened this block is raised whereas upon closing of the door the block is lowered, and by connecting the link 66 from this block 62 to the door P, corresponding movement will be imparted to this last mentioned door and thus as the door O is either opened or closed the door P will be likewise moved. To provide for automatic opening of the doors when the crane upright is raised, the friction roller 67 is mounted on the head thereof and a cam 69 is provided on the other side of the door O to be engaged by the friction 110 roller in such a manner that as the crane upright is extended upwardly the bearing engagement of the friction roller upon the cam 69 will cause the door O, and consequently the door P, to be moved to their full 115 120 125 130

open position. As has been previously stated, it is desirable that guard means be provided on one or both sides of the opening C, and in the present instance this guard means is illustrated as embracing the arms 70 and 71 carried by the underside of the doors O and P and made of such length that when the doors are opened they will overlap. The arm 71 carries a relatively short 10 pin 72 which springs into an opening 72' formed in the arm 70 near its outer end, when the doors O and P are completely open, to lock the arms against independent pivotal movement and to maintain the doors 15 O and P in the open position.

With the structure illustrated in Fig. 12, the doors O' and P' are hinged to close over the opening C in substantially the same manner as heretofore described, the guide or 20 trackway 65' is mounted substantially between the doors and the block 62' has vertical sliding movement therein. The link 61' is connected at one end with the door O' and at its remaining end with the block 62'. A 25 link 73 is connected at one of its ends with the block 62', and is arranged to stand at all times in a substantially vertical position. Slotted arms 74 and 75 are connected pivotally on the lower side of the doors O' and 30 P' with their slotted ends extending therefrom and overlapped, and a pin 76 carried by the upper end of the link 73 is passed through the slotted openings of these cross and pivotally mounted arms 74 and 75, the 35 arrangement of the parts being such that as the door O' is raised and the block 62' is consequently moved upwardly through the connection of the link 61', the link 73 will be moved vertically upwardly and through the 40 connection of the pin 76 through the slotted openings of the arms 74 and 75, these arms will be swung up to substantially the position illustrated in Fig. 14 to dispose a guard structure across outside of the opening C, 45 and to open the door P'.

As the description of the preferred and modified forms of the invention has been carried forward, a statement of the use and operation of the various structures has been 50 embodied in these forms, and it is therefore not thought that recapitulation need here be indulged in, but attention might be called to the fact that changes in details may be made without departing from the spirit and 55 scope of my invention; but

I claim:

1. An ash and refuse hoisting device including with supporting means to be mounted in a pit or basement, a crane upright slidably mounted in connection with the supporting structure, to be capable of raising and lowering movement and having a crane arm at the upper end thereof, a hoisting cable mounted over cable wheels provided on 60 the crane arm, a cable drum revolvably 65

mounted upon the supporting structure, a second cable drum mounted in connection with said first drum, a second cable given a double turn about said second drum, a counter-weight carried at one end of said second 70 cable, means having connection with the opposite end of said second cable by which the same is taken in, and a bracket associated with the crane upright against which the counter-weight engages to impart elevating 75 movement to said upright.

2. An ash and refuse hoisting device including with supporting means to be mounted in a pit or basement, a crane upright slidably mounted in connection with the supporting structure to be capable of raising and lowering movement and having a crane arm at the upper end thereof, a hoisting cable mounted over cable wheels provided on the crane arm, a cable drum revolvably 80 mounted upon the supporting structure, a second cable drum mounted in connection with said first drum, a second cable given a double turn about said second drum, a counter-weight carried at one end of 85 said second cable, means having connection with the opposite end of said second cable by which the same is taken in, a bracket associated with the crane upright against which the counter-weight engages to impart elevating 90 movement to said upright, and latch means to retain the crane upright in an elevated position.

3. An ash and refuse hoisting device including with supporting means to be 100 mounted in a pit or basement, a crane upright slidably mounted in connection with the supporting structure to be capable of raising and lowering movement and having a crane arm at the upper end thereof, a 105 hoisting cable mounted over cable wheels provided on the crane arm, a cable drum revolvably mounted upon the supporting structure, a second cable drum mounted in connection with said first drum, a second cable given a double turn about said second 110 drum, a counter-weight carried at one end of said second cable, means having connection with the opposite end of said second cable by which the same is taken in, a bracket associated with the crane upright against which the counter-weight engages to impart elevating 115 movement to said upright, latch means to retain the crane upright in an elevated position, and means to impart a partial turn to the crane upright to swing the arm thereof to clear the opening.

4. An ash and refuse hoisting device including with supporting means to be mounted in a pit or basement, a crane upright slidably mounted in connection with the supporting structure to be capable of raising and lowering movement and having a crane arm at the upper end thereof, a 125 hoisting cable mounted over cable wheels 130

provided on the crane arm, a cable drum revolubly mounted upon the supporting structure, a second cable drum mounted in connection with said first drum, a second cable given a double turn about said second drum, a counter-weight carried at one end of said second cable, means having connection with the opposite end of said second cable by which the same is taken in, a bracket associated with the crane upright against which the counter-weight engages to impart elevating movement to said upright, latch means to retain the crane upright in an elevated position, and means to insure maintenance of a straight drawing tension upon said cables irrespective of the length of the same which may be taken in.

5. An ash and refuse hoisting device including with supporting means located in a pit or basement, a crane upright slidably mounted in conjunction with the supporting structure to be capable of elevation to extend from the pit, a cylinder mounted within the pit and having a piston therein to be moved by fluid pressure, a connection from this piston by which the crane upright is raised, a fluid supply pipe by which fluid under pressure is led to said cylinder, and valves in the fluid supply pipe by which the supply of fluid can be controlled from within the pit and from a level above the pit.

6. An ash and refuse hoisting device including with supporting means located in a pit or basement, a crane upright slidably mounted in conjunction with the supporting structure to be capable of elevation to extend from the pit, a cylinder mounted within the pit and having a piston therein to be moved by fluid pressure, a connection from this piston by which the crane upright is raised, a fluid supply pipe by which fluid under pressure is led to said cylinder, valves in the fluid supply pipe by which the supply of fluid can be controlled from within the pit and from a level above the pit, and means to cushion the movement of the piston within the cylinder.

7. An ash and refuse hoisting device adapted to be installed for use in a pit or basement having an opening therefrom including supporting structure mounted within the pit, a crane upright slidably mounted in conjunction with the supporting structure and having an arm at the upper end thereof, a shaft mounted upon the supporting structure, large and small cable drums mounted upon said shaft to turn together, a cable connected with the larger drum extended over the arm of the crane upright and having an attaching hook on the free end thereof, a bracket member carried by said crane upright, a second cable wound about the smaller drum and having one end thereof loosely passed through an opening of the bracket member, a counter-weight connected

with the end of said second cable, a cylinder mounted within the pit, a piston mounted slidably within the cylinder and with which the free end of the second mentioned cable has attachment, a fluid supply pipe connected with the cylinder through which fluid under pressure is discharged thereto, and a three-way valve connected in said pipe to control the supply of fluid under pressure to the cylinder and exhaust the same therefrom.

8. An ash and refuse hoisting device adapted to be installed for use in a pit or basement having an opening therefrom including supporting structure mounted within the pit, a crane upright slidably mounted in conjunction with the supporting structure and having an arm at the upper end thereof, a shaft mounted upon the supporting structure, large and small cable drums mounted upon said shaft to turn together, a cable connected with the larger drum extended over the arm of the crane upright and having an attaching hook on the free end thereof, a bracket member carried by said crane upright, a second cable wound about the smaller drum and having one end thereof loosely passed through an opening of the bracket member, a counter-weight connected with the end of said second cable, a cylinder mounted within the pit, a piston mounted slidably within the cylinder and with which the free end of the second mentioned cable has attachment, a fluid supply pipe connected with the cylinder through which fluid under pressure is discharged thereto, and a three-way valve connected in said pipe to control the supply of fluid under pressure to the cylinder and exhaust the same therefrom.

9. An ash and refuse hoisting device adapted to be installed for use in a pit or basement having an opening therefrom including supporting structure mounted within the pit, a crane upright slidably mounted in conjunction with the supporting structure and having an arm at the upper end thereof, a shaft mounted upon the supporting structure, large and small cable drums mounted upon said shaft to turn together, a cable connected with the larger drum extended over the arm of the crane upright and having an attaching hook on the free end thereof, a bracket member carried by said crane upright, a second cable wound about the smaller drum and having one end thereof loosely passed through an opening of the bracket member, a counter-weight connected with the end of said second cable, a cylinder mounted within the pit, a piston mounted slidably within the cylinder and with which the free end of the second mentioned cable has attachment, a fluid supply pipe connected with the cylinder through which fluid under pressure is discharged thereto, and a three-way valve connected in said pipe to control the supply of fluid under pressure to the cylinder and exhaust the same therefrom, and means to cushion movement of the piston and to regulate the speed of action thereof.

10. An ash and refuse hoisting device adapted to be installed for use in a pit or basement having an opening therefrom including supporting structure mounted within the pit, a crane upright slidably mounted in conjunction with the supporting structure and having an arm at the upper end thereof, a shaft mounted upon the supporting structure, large and small cable drums mounted upon said shaft to turn together, a cable connected with the larger drum extended over the arm of the crane upright and having an attaching hook on the free end thereof, a bracket member carried by said crane upright, a second cable wound about the smaller drum and having one end thereof loosely passed through an opening of the bracket member, a counter-weight connected with the end of said second cable, a cylinder mounted within the pit, a piston mounted slidably within the cylinder and with which the free end of the second mentioned cable has attachment, a fluid supply pipe connected with the cylinder through which fluid under pressure is discharged thereto, and a three-way valve connected in said pipe to control the supply of fluid under pressure to the cylinder and exhaust the same therefrom.

connected with the cylinder through which fluid under pressure is discharged thereto, a three-way valve connected in said pipe to control the supply of fluid under pressure 5 to the cylinder and exhaust the same therefrom, and means to retain the crane arm in the raised position.

10. In an ash and refuse hoisting device for use in a pit or basement having an opening therefrom, a supporting structure 10 mounted within the pit, a crane upright carried by said supporting structure and mounted for extension through the opening, means by which the crane upright is raised 15 to its extended position, and means to impart a partial turn to the crane upright when in an extended position to swing the arm thereof to clear the opening, and latch means to retain the crane upright in an elevated position.

11. In an ash and refuse hoisting device adapted for use in a pit or basement having an opening therefrom, a supporting structure mounted within the pit, a crane upright carried by the supporting structure and mounted to be capable of extension through the opening, means by which the crane upright is raised to its extended position, a supporting bracket for said crane 25 upright, a pair of links pivotally carried by said bracket, and rollers carried by said links and adapted to swing into engagement beneath the lower end of said crane when the latter reaches the limit of its upward 30 movement.

12. In an ash and refuse hoisting device adapted for use in a pit or basement having an opening therefrom, a supporting structure mounted within the pit, a crane upright carried by the supporting structure and mounted to be capable of extension through the opening, means by which the crane upright is raised to its extended position, a supporting bracket for said crane 40 upright, a pair of links pivotally carried by said bracket, and rollers carried by said links and adapted to swing into engagement beneath the lower end of said crane when the latter reaches the limit of its upward 45 movement, and means to impart a partial turn to the crane upright when in an extended position.

13. In an ash and refuse hoisting device adapted for use in a pit or basement having 55 an opening therefrom, supporting means mounted in the pit or basement, a crane upright slidably mounted in connection with said supporting structure to be capable of raising and lowering movement, a crane arm 60 at the upper end of said crane upright, a hoisting cable mounted over cable wheels carried by the crane arm, a crane cable drum revolvably mounted upon the supporting structure, a second cable drum mounted in 65 connection with said first drum, a second

cable given a double turn about said second drum, a counter-weight carried at one end of said second cable, means having connection with the opposite end of said second cable by which the same is taken in, a 70 bracket associated with the crane upright against which the counter-weight engages to impart elevating movement to said upright, a supporting bracket for said crane upright, a pair of links pivotally carried by 75 said supporting bracket, and rollers carried by said links and adapted to swing into engagement beneath the lower end of said crane when the latter reaches the limit of its upward movement.

14. In an ash and refuse hoisting device adapted for use in a pit or basement having an opening therefrom, supporting means mounted in the pit or basement, a crane upright slidably mounted in connection with 80 said supporting structure to be capable of raising and lowering movement, a crane arm at the upper end of said crane upright, a hoisting cable mounted over cable wheels carried by the crane arm, a crane cable drum 85 revolvably mounted upon the supporting structure, a second cable drum mounted in connection with said first drum, a second cable given a double turn about said second drum, a counter-weight carried at one 90 end of said second cable, means having connection with the opposite end of said second cable by which the same is taken in, a bracket associated with the crane upright against 95 which the counter-weight engages to impart elevating movement to said upright, a supporting bracket for said crane upright, a pair of links pivotally carried by 100 said supporting bracket, and rollers carried by said links and adapted to swing into engagement beneath the lower end of said crane when the latter reaches the limit of its upward 105 movement, and means to insure maintenance of the straight drawing tension upon said cable.

15. In an ash and refuse hoisting device, a supporting means located in a pit or basement, a crane upright slidably mounted in conjunction with said supporting structure to be capable of elevation to extend from 110 the pit, a cylinder mounted within the pit and having a piston therein to be moved by fluid pressure, a connection from this piston by which the crane upright is raised, a fluid supply pipe by which fluid under 115 pressure is led to said cylinder, valves in the fluid supply pipe by which a supply of fluid can be controlled from within the pit and from a level above the pit, latch means to retain the crane upright in an elevated position, a crane arm at the upper end of the 120 upright, and means to impart a partial turn to the crane upright to swing the arm thereof to clear the opening.

16. In an ash and refuse hoisting device, 130

a supporting means located in a pit or basement, a crane upright slidably mounted in conjunction with the supporting means to be capable of elevation to extend from the 5 pit, a cylinder mounted within the pit and having a piston therein to be moved by fluid pressure, a connection from this piston by which the crane upright is raised, a fluid supply pipe by which fluid under pressure 10 is led to said cylinder, a valve carried by said crane upright, branch pipes connected to said fluid supply pipe, flexible conduits communicating with said crane carried valve and said branch pipe whereby the supply of 15 fluid can be controlled from the level above the pit.

17. In an ash and refuse hoisting device, a supporting means located in a pit or basement, a crane upright slidably mounted in 20 conjunction with the supporting means to be capable of elevation to extend from the pit, a cylinder mounted within the pit and having a piston therein to be moved by fluid pressure, a connection from this piston 25 by which the crane upright is raised, a fluid supply pipe by which fluid under pressure is led to said cylinder, a valve carried by said crane upright, branch pipes connected to said fluid supply pipe, flexible conduits 30 communicating with said crane carried valve and said branch pipe whereby the supply of fluid can be controlled from the level above the pit, a valve in the fluid supply pipe whereby the supply of fluid can be controlled 35 from within the pit, a supporting bracket for said crane upright, a pair of links pivotally carried by said bracket, and roller carried by said links and adapted to swing into engagement beneath the lower end of the crane when the latter reaches the 40 limit of its upward movement, latch means for engagement with the lower end of the crane when the latter is in an elevated position, and means to impart a partial turn to crane upright when in an elevated position. 45

18. In an ash and refuse hoisting device, a supporting means located in a pit or basement, a crane upright slidably mounted in 45 conjunction with the supporting means to

be capable of elevation to extend from the pit, a cylinder mounted within the pit and having a piston therein to be moved by fluid pressure, a connection from this piston by which the crane upright is raised, a fluid supply pipe by which fluid under pressure is led to said cylinder, a valve carried by said crane upright, branch pipes connected to said fluid supply pipe, flexible conduits communicating with said crane carried valve 55 and said branch pipe whereby the supply of fluid can be controlled from the level above the pit, a valve in the fluid supply pipe whereby the supply of fluid can be controlled from within the pit, a supporting 60 bracket for said crane upright, a pair of links pivotally carried by said bracket, and roller carried by said links and adapted to swing into engagement beneath the lower end of the crane when the latter reaches the 65 limit of its upward movement, latch means for engagement with the lower end of the crane when the latter is in an elevated position, and means to impart a partial turn to crane upright when in an elevated position. 70

19. In an ash and refuse hoisting device, supporting means located within a pit or basement, a crane upright slidably mounted in conjunction with the supporting structure to be capable of elevation to extend from 75 the pit, a cylinder mounted within the pit and having a piston therein to be moved by fluid pressure, a connection from this piston by which the crane upright is raised, a crane arm carried by the upper end of 80 the crane upright, means for supplying fluid under pressure to said cylinder, means whereby the supply of fluid to the cylinder may be controlled within the pit or from a level above the pit, latch means to retain the 85 crane upright in an elevated position, and means to impart a partial turn to the crane upright to swing the arm thereof to clear the opening.

JOHN M. BARNEY.
